Des. 238,858

Patented Feb. 17, 1976

238,858

HAND HELD OPTICAL CHARACTER RECOGNITION SCANNING UNIT

Rodney Barclay, Richardson, and Robert B. Koenig,
Dallas, Tex., assignors to Recognition Equipment In-
corporated, Irving, Tex.

Filed Jan. 17, 1974, Ser. No. 434,192

Term of patent 14 years

Int. Cl. D10—04

U.S. Cl. D10—46

Figure 3

Figure 1

Figure 2

Figure 4

FIG. 1 is a right side elevational view of a hand held optical character recognition scanning unit showing our new design, the left side, not shown, being a mirror image thereto;

FIG. 2 is a front elevational view thereof;

FIG. 3 is a top plan view thereof; and

FIG. 4 is a bottom plan view thereof.

We claim:

The ornamental design for a hand held optical character recognition scanning unit, as shown.
